UNITED STATES PATENT OFFICE

97,044

DESIGN FOR A LADY'S SWEATER

Bernard Epstein, New York, N. Y.

Application August 27, 1935, Serial No. 58,313

Term of patent 3½ years

To all whom it may concern:

Be it known that I, Bernard Epstein, a citizen of the United States of America, residing in Manhattan, county of New York, and State of New York, have invented a new, original, and ornamental Design for a Lady's Sweater, of which the following is a specification, reference being had to the accompanying drawing, forming part thereof, wherein,

Figure 1 is a front view of a lady's sweater showing my new design.

Figure 2 is a rear view of the lady's sweater shown in Figure 1.

Figure 3 is a front view of the collar portion of the lady's sweater shown in Figure 1, showing the collar in a turn down position.

The dominant feature of the design resides in the collar structure of the pull-over sweater, which collar has a similarly arcuate notch at the upper and lower front sections thereof, and which notches are adapted to coincide when the collar is in a turned down position.

I claim:

The ornamental design for a lady's sweater, substantially as shown, and described.

BERNARD EPSTEIN.
